(57) **CLAIM**

I claim the ornamental design for a water throwing device, as shown and described.

DESCRIPTION

FIG. 1 is a perspective view of a water throwing device showing my new design;

FIG. 2 is a top plan view thereof;

FIG. 3 is a bottom plan view thereof;

FIG. 4 is a right-side elevation view thereof;

FIG. 5 is a left-side elevation view thereof;

FIG. 6 is a front elevation view thereof; and,

FIG. 7 is a back elevation thereof.
